GEAR CASE

Application filed July 28, 1927. Serial No. 209,144.

This invention has for its object the provision of a simple and efficient device whereby a train of gearing will be protected against access of dirt and other foreign matters and will be permitted to operate in a lubricant. The invention is designed primarily for use upon corn-husking machines to house the gearing connecting the upper ends of snapping rolls but it may be employed advantageously in other fields wherever it is applicable. One embodiment of the invention is illustrated in the accompanying drawings and will be hereinafter fully described, the novel features being subsequently particularly pointed out in the appended claims.

In the drawings:

Figure 1 is a plan view of a gear case constructed in accordance with our present invention;

Fig. 2 is an end view partly broken away;

Fig. 3 is a vertical section taken substantially upon the line 3—3 of Fig. 1;

Fig. 4 is a view, partly in bottom plan and

partly in section, on the line 4—4 of Fig. 3,

and

Fig. 5 is a detail section on the line 5—5 of Fig. 3.

In the drawings, the reference numerals 1 and 2 respectively indicate frame bars of a corn-husking machine, the bar 1 being at times referred to, for convenience, as the upper bar and the bar 2 being designated as the lower bar. The bars 1 and 2 are arranged in pairs at the sides of the machine and converge toward their upper ends which are connected by gusset plates 3 which extend upwardly beyond the frame bars, as shown clearly in Fig. 2, a very strong and rigid structure being thereby attained. The upper end of each gusset plate is constructed with a lateral flange 4 and below the upper extremity of the upper frame bars 1 a cross bar 5 is secured to and extends between said bars, the cross bar being preferably in the form of an angle bar having its depending flange cut away at its ends whereby it may fit to and extend over the edges of the gusset plates and rest upon the frame bars 1. The snapping rolls, indicated at 6, are arranged in pairs and are equipped

with trunnions 7 which pass through journal

boxes 8, the said journal boxes being fitted in a yoke 9 which extends across and rests upon the cross bar 5, the yoke being secured in place by being bolted to the said cross bar and to the flanges of the frame bars 1. Power is applied to the lower end of the inner roll of each pair of rolls and this roll may be considered as a driving roll while the outer roll of each pair may be considered as a driven roll, the journal box through which the trunnion of the driven roll passes being slidably supported in the yoke and yieldably held at the inward limit of its movement by means which are well known to those skilled in the art. The trunnions of the snapping rolls are operatively connected through trains of gearing which include stub shafts, indicated at 10 and 11 and disposed below the ends of the trunnions. Gears, indicated at 12 and 13, are secured upon the trunnions of the driving and the driven rolls, respectively, and mesh with gears 14 and 15 upon the respective stub shafts, one of the stub shafts having a gear 16 which meshes with the gear 14 upon the mating stub shaft so that the motion will be transmitted from the driving to the driven roll while at the same time permitting the relative sliding movement of the driven roll. The particular purpose of the present invention is to provide a case which will house the trunnions, stub shafts and gearing and permit them to be submerged in lubricant so that they will operate easily and effectually at all times, the construction of the case being such that it will not add very materially to the dead weight of the machine and it may be readily mounted upon the machine to support the stub shafts and the idler gears carried thereby at a comparatively low cost.

In constructing the gear case, we employ a bottom 17 which is preferably a casting having a flange 18 extending entirely around its margin and constructed adjacent its ends with longitudinal slots 19 receiving the trunnions of the relatively movable rolls. The bottom is, of course, provided with openings to accommodate the trunnions of the driving rolls and also the ends of the stub shafts 10 and 11 which project therethrough and may be equipped with integral sockets or

lubricant boxes 20 whereby lubricant may be supplied thereto in an obvious manner. The bottom plate 17 rests against the depending flange of the cross bar 5 and bears against and extends between the gusset plates 3 and suitable bolts are inserted through the bottom and the flange of the cross bar 5 as well as through the flange of the bottom and the gusset plates to secure the bottom plate rigidly in place. The bottom plate is also provided with an integral elliptical rib 21 on its inner or upper side which is disposed coincident with the slot 19 and rising from the bottom to an extent approximately equal to the length of the trunnion 7 which extends into the case, as will be understood upon reference to Fig. 3. This construction amply accommodates the relative lateral movement of the trunnion of the outer snapping roll and at the same time provides a support for the trunnion which will counteract any tendency of the same to bend within the gear case while in use. Furthermore, it removes the upper or inner opening to a point within the gear case so that the lubricant therein cannot pass out through the bottom of the case and the case may be filled to a level very nearly the same as the highest point reached by any of the gears. It is desirable to prevent flow of lubricant to the slot 19 as the trunnion shifts therein and exposes part of the slot and for that purpose we provide a sealing plate 22 which is fitted to the upper extremity of the trunnion immediately adjacent the hub of the gear secured thereon, and this sealing plate rests upon and slides on the upper edge of the rib and is of such extent that the space within the rib will at all times be entirely covered and, consequently, the lubricant cannot escape through the rib and be lost. Fitted close within the marginal flange 18 of the bottom 17 are side and end walls which are preferably constructed of sheet metal, to reduce cost, and these side and end walls consist of a lower member 23 and an upper member 24 each of which is a flat plate having its ends bent at a right angle to its greater length, the ends overlapping when the side and end walls are placed in position and being firmly bolted together. These side and end wall members are of such dimensions that they will fit snugly within the marginal flanges 18 and they are secured to the gusset plates by the same bolts which secure the said flanges to said plates. The top of the gear case consists of a lower section 25 and an upper section 26 both of which are sheet metal plates, the lower section 25 being a flat plate of sufficient size to extend entirely across the gear case and rest upon the upper edges of the side and end member 23 and also project beyond the same and rest upon the flanges 4 of the gusset plates to which it is firmly secured. This lower plate 25 is also provided with openings

therethrough corresponding in position and arrangement to the location of the stub shafts carrying the gears 14, 15 and 16 and thereby serving to retain the said shafts and their gears in operative positions. The upper section 26 of the top is provided around three edges with a flange 27 fitted about the upper side and end walls 24 so that the said section 26 may be readily placed in its proper position, the flanges being slightly cut away or shortened at their extremities to accommodate the flanges of the gusset plates and the projecting ends of the lower sections 25, as shown in Fig. 2. The lower edge of the upper top section 26 overlaps the upper edge of the lower top section 25, as shown clearly in Fig. 3, so that leakage of the lubricant placed in the case is avoided, and to retain the parts in the proper position under cut lugs or brackets 28 are provided on the inner side of the said section 26 adjacent the lower edge thereof to engage under the upper edge of the section 25, also as shown in Fig. 3. To secure the section 26 in its position, a right angle bracket or projection 29 is provided on the top of the wall member 24 and a similar projection or bracket 30 is rigidly secured to the upper side of the said top section 26, openings being formed through the mating extremities of these brackets to receive a bolt 31 on which is mounted a wing nut 32 adapted to be turned home against the adjacent bracket. The top section 26 is thus securely held in place but it may be easily removed when necessary to inspect the gears or to replenish the supply of lubricant.

While the elliptical rib 21 provided around the slot 19 serves as a means for limiting the movement of the trunnion passing therethrough, it is desirable to provide additional means for limiting the relative outward movement of said trunnion and for that purpose we form on the under side of the bottom 17 a lug 33 immediately adjacent the outer end of the slot 19, as shown most clearly in Fig. 4, so that when the trunnion moves outwardly it will abut the said stop lug, the strain upon the spring which normally holds the trunnion in its inner position being thereby relieved and the possibility of fracture occurring in the rib 21 being reduced.

From the foregoing description, taken in connection with the accompanying drawings, it will be seen that we have provided a very simple gear case which will effectually house the gearing connecting the upper ends of snapping rolls and effectually protect the same from damage through chance blows while preventing the access of dirt and other foreign matter thereto and which gear case can be produced and applied at a low cost. The device is especially advantageous because it will permit the trains of gears to be almost entirely submerged in lubricant.

Upon reference to Fig. 3, it will be noted that the highest point on the highest gear 13 is only slightly above the horizontal plane of the joint between the upper and lower sections of the top of the case and, consequently, the case may be filled with lubricant to almost its complete capacity, it being understood that the lubricant is what is known as a hard oil or grease which will not flow like liquid and, consequently, will not readily seep or leak through the joint between the upper and lower sections of the side and end walls. This joint, furthermore, may be made practically tight by turning home the nuts 5 on the securing bolts so that any leakage which may possibly occur will be so slight as to be negligible. While the lubricant is being placed in the case, the upper section 10 of the top is, of course, removed thereby exposing the space above the lower top section 25, and the lubricant is filled into the case through this open space. After the case has been filled with the lubricant, the section 26 is, of course, replaced and secured. The 15 manner in which the gear case is secured to the several elements of the supporting frame holds it very effectually in its proper place and resists vibration in a highly efficient manner so that distortion of the case through use 20 is not apt to occur and the trains of gearing will be always in proper mesh and will operate readily without binding strain.

Having thus described the invention, we claim:

35 1. The combination with a driving rotatable element, a driven rotatable element movable bodily toward and from the driving element, and a train of gears operatively connecting said elements, of a case housing said elements and said gears and having a slot in one side through which the driven element passes, an elliptical rib on the inner surface of the slotted side of the case coincident with the slot, and a sealing plate 40 carried by the driven element and extending entirely over and slidably resting on the inner edge of said rib.

2. The combination with a driving rotatable element, a driven rotatable element movable bodily toward and from the driving element, and a train of gears operatively connecting said elements, of a case housing said elements and said gears and having a slot in one side through which the driven element passes, a sealing plate carried by said element within the case and covering said slot, and a stop on the outer surface of the slotted side of the case at the outer end of the slot therein.

60 3. The combination of pairs of frame bars, gusset plates each secured to the meeting ends of the bars of one pair of bars and extending upwardly beyond the same, a cross bar secured upon and extending between the 65 upper bars of the pairs of bars, a bottom dis-

posed between the gusset plates and resting upon and secured to said cross bar and bearing at its ends against and secured to the gusset plates, side and end walls resting on said bottom and secured to the same and to 70 the gusset plates, a top including a lower section resting on the upper edges of the side and end walls and the upper ends of the gusset plates and secured to the gusset plates and an upper section resting on the upper 75 edges of the side and end walls with its lower edge overlapping the upper edge of the lower section, and means for fastening the upper section to an adjacent side wall, the bottom and the lower section of the top having axially aligned openings therethrough for rotatable elements, and the bottom having openings above the cross bar to receive other rotatable elements which are supported by the cross bar.

4. The combination with a driving rotatable element, a driven rotatable element movable bodily toward and from the driving element, and a train of gears operatively connecting said elements, of a case housing 80 said elements and said gears and having a slot in one side through which the driven element passes, and an elliptical rib on the inner surface of the slotted side of the case coincident with the slot.

In testimony whereof we affix our signatures:
